Patented June 10, 1969

214,378

COMBINED AMPERE, VOLT AND RESISTOR-METER

Yoshiharu Alan Shimasaki, 5-12, 3-chome Minami-
Azaba, Minato-ku, Tokyo, Japan

Filed Nov. 14, 1967, Ser. No. 9,400

Term of patent 14 years

Int. Cl. D10—10

U.S. Cl. D26—1

Fig. 1

Fig. 2

Fig. 3

Fig. 4

FIG. 1 is a front view of 2 combined ampere, volt and resistor-meter embodying my invention.

FIG. 2 is a top view thereof.

FIG. 3 is a back view thereof.

FIG. 4 is a bottom view thereof.

FIG. 5 is a left side view thereof.

FIG. 6 is a right side view thereof.

FIG. 7 is a sectional view thereto taken along line 7—7 of FIG. 1.

I claim:

The ornamental design for a combined ampere, volt and resistor-meter, as shown.
